UNITED STATES PATENT OFFICE.

THOMAS J. BARBRE, OF DENVER, COLORADO.

PNEUMATIC ROCK-DRILL.

1,092,237.

Specification of Letters Patent. Patented Apr. 7, 1914.

Application filed March 22, 1912. Serial No. 685,486.

To all whom it may concern:

Be it known that I, THOMAS J. BARBRE, a citizen of the United States, residing in the city and county of Denver and State of Colorado, have invented certain new and useful 5 Improvements in Pneumatic Rock-Drills; and I do declare the following to be a full, clear, and exact description of my invention, such as will enable others skilled in the art 10 to which it appertains to make and use the same, reference being had to the accompanying drawings, and to the figures of reference marked thereon, which form a part of this specification.

15 My invention relates to improvements in pneumatic rock drills and has for its object the provision of a device of this character, whose parts are simple and inexpensive in manufacture.

20 Another object of my invention is to provide a simple and effective valve for controlling the induction of the motive fluid alternately to the front and rear of the piston.

Another object of my invention is to provide 25 simple and effective means for supplying lubricant to the various parts of the rock drill.

Still another object of my invention resides in the provision of a rock drill whose 30 parts are positive in operation.

With these and other objects in view, I will proceed to describe my invention with reference to the accompanying drawings forming a part hereof.

35 In the drawings:—Figure 1 is a longitudinal section of my improved rock drill, showing the valve applied to the motor. Fig. 2 is a similar view, showing the valve in a different relative position. Fig. 3 is a 40 plan view of my improved rock drill, showing the parts in their assembled relation. Fig. 4 is a sectional detail view of a valve employed for controlling the motive fluid to the motor and feed cylinder. This valve 45 also serves to admit lubricant to the drill. Fig. 5 is a similar view, showing the valve in a different relative position. Fig. 6 is a longitudinal section of the valve for controlling the induction of the motive fluid to the front 50 and rear of the piston. Fig. 7 is a plan view of the valve piece employed for controlling the motive fluid supply.

The same reference characters represent the same parts in all the views.

55 Referring, first, to Fig. 3, let the numeral 5 designate the feed cylinder of my im-

proved rock drill and the numeral 6 the motor thereof. The feed cylinder 5 and the motor 6 are connected together, in operative relation, by means of rods or bolts 7 passed 60 through ears 8 and 9, respectively formed on the motor and feed cylinder. Interposed between the motor and feed cylinder, I arrange a valve housing, designated in its entirety, by the reference character 10. See 65 Figs. 1 and 2. This valve housing is provided with a centrally located opening 12, in which I arrange a reciprocal valve piece 13. This valve piece 13 is known as the spool type; and while it may be old to employ a 70 spool type valve, in a rock drill, for controlling the motive fluid to the drill, there are certain features of novelty embodied in the valve piece employed by me which accomplish effective and positive operation of the 75 valve piece. These novel features also obviate many delicate parts which have heretofore been employed in drills of this character and as a consequence influence the operation of the drill, for the better.

The operation of the valve piece 13, for controlling the induction of the motive fluid to the front and rear of the piston will be more clearly described and understood by reference to Figs. 1 and 2, in which figures 85 the various ports and passages are illustrated. In Fig. 1, I have shown the position of the valve piece 13, to admit motive fluid from the feed pipe 14, to the rear of the piston 15, for the forcing of the said piston forwardly into engagement with a drill steel 16, which is arranged in the forward extremity of a cylinder 17 of the motor 6, while in Fig. 2, I have shown the position of the valve 90 piece 13 to admit motive fluid forward of the piston 16, for forcing the said piston rearwardly. These two positions of the valve piece 13 respectively admit the motive fluid rearwardly and forwardly of the piston 15 and by virtue of means, hereinafter described, for changing the position of the 95 said valve piece, the motive fluid is alternately admitted rearwardly and forwardly of the piston 15, whereby a constant reciprocation of the compression is maintained in 100 105 the piston 17.

Before going into the operation of my improved drill, I wish to state that the valve housing 10 is inclosed by a cap 18, and that this cap is provided with a passage 19, 110 which leads from the motive fluid supply pipe 14. This cap 18 serves as a protection

for the valve housing 10 and the valve piece 13 and also serves as a partition or means of separating the feed cylinder 5 from the motor 6. Now, assuming that the 5 valve piece 13 is in the position illustrated in Fig. 1, and that the motive fluid has been turned on by means of a valve 20, the construction of which will be hereinafter explained, the motive fluid enters through the 10 passage 19, formed in the cap 18, and thence through the passage 21, formed in the valve housing 10, and registering with the passage 19. From the passage 21, the motive fluid passes into the cylinder 17, in the rear of the piston 15, and forces the piston 15 forwardly into engagement with the drill steel or tappet 16. As soon as the piston 15 has moved forwardly far enough to uncover a 15 port 22, formed about centrally of the cylinder 17, the motive fluid passes through this port and a passage 23, formed in the wall of the cylinder, to the rear of the valve piece 13, through a port 24, and moves the valve piece to the position indicated in Fig. 20 25, whereupon the motive fluid, from the passage 19, will pass through perforations 25 formed in the flange 26 of the valve piece 13, to the interior, or hollow 27 thereof, and from the hollow 27, through perforations 28, formed in a shoulder 29 of the valve piece 13, into a circumferential passage 30, formed in the valve housing 10. From this circumferential passage 30, the 30 live motive fluid will pass through a port 31, to a longitudinally disposed passage 32, which leads through the wall of the cylinder 17 and communicates with the interior of the cylinder 17, near the forward extremity of the latter through a port 33. Thus the live motive fluid enters the cylinder 17 forwardly of the piston 15 and forces the latter rearwardly. As the piston 15 is moving rearwardly, the air in the rear of the piston will exhaust through a port 34 35 into a passage 35 and thence through a port 36 and a circumferential groove 37 formed in the valve housing surrounding the opening 12 in the latter. The valve-housing 10 is provided with a passage 38 which communicates with the atmosphere through the cap 18, as shown at 39. Consequently when the exhaust has entered the opening 12 between the shoulders, or flanges 26 and 29, of the valve piece 13, it will pass through 40 this passage 38 to the atmosphere. However, as soon as the piston 15 has moved rearwardly far enough to cover the port 34, the exhaust will be cut off and the piston will then compress the motive fluid between the piston and the rear end of the cylinder and this compression will normally act upon the valve piece 13 to shift the latter to the position illustrated in Fig. 1, but if for any reason this compression does not

shift the valve piece 13, the piston 15 will 65 strike a projection 40, formed on the inner extremity of the valve piece, to the position illustrated in Fig. 1, which will thus bring about the condition first explained in connection with Fig. 1, or in 70 other words, will establish communication of the live motive fluid with the interior of the cylinder 17 in the rear of the piston 15.

From the foregoing described two positions of the valve piece 13, it will be readily understood that this valve piece will be alternately shifted to the two positions for alternately establishing communication of the live motive fluid with the interior of the cylinder 17 in the rear and front of the 80 piston 15, whereby this piston 15 is kept constantly reciprocating and on each forward stroke strikes the tappet, or drill steel 16, which forces the latter into the rock or other material in which the hole is being 85 drilled.

I wish to call special attention to the construction of my valve piece, which is designated in the drawings by the reference character 13. This valve piece is hollow and the 90 induction of the live motive fluid to the interior of the cylinder 17, forwardly of the piston 15, is established through the hollow of this valve piece. By virtue of the spool-shaped valve employed, the frictional contact of the valve piece, with the housing 10, is reduced to a minimum and goes far toward insuring the positive operation of the said valve piece.

By virtue of the circumferential grooves 100 arranged on the interior of the valve housing 10, and surrounding the opening 12, the motive fluid is allowed to pass around these passages and serve to balance the valve piece 13. In other words, when the induction of 105 the motive fluid passes out of the various induction passages into contact with the valve piece 13, it is distributed evenly around the said valve piece instead of exerting all of its pressure or force on the 110 valve piece 13 at one particular point.

I will now proceed to describe the means for controlling the induction of the motive fluid to the feed cylinder 5 and the motor 6. To the cap 18, I connect a valve housing 41, 115 into which the supply pipe 14 leads. In this housing 41, the valve 20 is arranged and it is by virtue of this valve 20 that the induction of the live motive fluid, to the feed cylinder 5 and the motor 6, is controlled. Connected with this housing 41, is a handle or operating member 42, which is hollow and is adapted to contain a supply of lubricant introduced thereto through a port or opening 43, which is closed by a screw plug 54. The 120 valve 20 is constructed so as to introduce a limited amount of the lubricant through the induction passage 19 into the motor, when-

ever the valve piece is turned to establish communication of the motive fluid with the motor. In Fig. 4 I have illustrated a detailed view of the valve 20, and the housing 41 and in this view, the valve piece 20 is shown in position to cut off the motive fluid from both the feed cylinder 5 and the motor 6, however, the valve piece 20 is provided with a recess 44 formed therein and which is 5 in communication with the interior of the handle 42, through a port 45, when the valve piece 20 is in the position to cut off the motive fluid from the feed cylinder 5 and the motor 6. Now assuming that it is desired to 10 start the rock drill in operation, the handle 46 of the valve piece 20, is turned to the dotted line position indicated in Fig. 5, whereby an opening 47, formed in the valve piece 20, is brought into communication with a passage 48, leading to the feed cylinder 5, through the cap 18. When the valve piece 20 is in this position the live motive fluid 15 will pass from the supply pipe 14, through a passage 49, formed in the housing 41, and a passage 50, formed in the valve piece 20 and thence through the passage 47 of the valve piece and passage 48, of the cap 18, to the interior of the feed cylinder 5, whereby the 20 drill is caused to move into engagement with the rock or material to be drilled, by virtue of the fact that the compression of the motive fluid in the feed cylinder 5 will cause the said cylinder to move on a piston 51. It is understood that this piston 51 is normally 25 engaged with a support or the ground opposite to the point where the hole is to be drilled and consequently the rock drill is constantly moved toward the material in which the hole is being drilled. Now as soon 30 as the communication of the live motive fluid has been established with the feed cylinder 5, in the manner above described, a further turning of the valve piece 20 will result in bringing an opening 52, formed in the valve piece 20, into communication with the passage 19, leading to the motor. When the valve piece 20 has been thus turned so that its opening 52 communicates with the induction passage 19, the motive fluid will pass 35 40 from the supply pipe 14, through the passage 19, of the housing 41, opening 50, of the valve piece 20 and opening 52, of the said valve piece and thence through the induction passage 19 in the manner heretofore described. At the same time that the communication of the motive fluid is established 45 with the motor, induction of the motive fluid is also established with the feed cylinder through the opening 47 of the valve piece 50 and passage 48 of the cap 18. When the valve piece 20 has been turned to the position, indicated in Fig. 5, the recess 44 has 55 also been brought into communication with a recess 53, formed in the housing 41 adja-

cent the valve sleeve and communicating 65 with the induction passage 19, whereby the oil or lubricant, which is passed from the hollow handle 42, into this recess 44, through the port 45, when the valve piece occupies the position shown in Fig. 4, will now pass 70 from this recess 44, by gravity, and the recess 53 into the induction passage 19 and will be carried into the motor with the induction of the live motive fluid thereto.

Of course, it is necessary to set the drill 75 before the motive fluid is turned into the motor and this is accomplished by establishing communication of the motive fluid with the feed cylinder before establishing communication of the motive fluid with the motor, in 80 the manner above described.

Attention is here called to the fact that I form a relatively small passage 55, in the flange 29 of the valve piece 13, whereby the motive fluid, which has passed to the rear of 85 the valve piece for forcing the latter forwardly, is permitted to leak out through the passage 55, between the two flanges 29 and 26 and out through the passage 38 to the atmosphere while the valve piece 13 is moving rearwardly under the influence of the motive fluid in the cylinder 17 in the rear of the piston 15. Thus as soon as the compression takes place in the cylinder in the rear of the piston 15, the valve piece 13 will be 90 freely moved rearwardly under the influence of the compression for establishing communication of the motive fluid with the forward extremity of the cylinder 17 in front of the piston.

Attention is here called to the fact that as the piston 15 moves forwardly the air in the cylinder 17 in front of the said piston will exhaust through the port 38, passage 32 and port 31, into the opening 12 and out through 105 the passage 38 to the atmosphere.

While I have described and illustrated herein a specific form of my invention, it must be understood that I am not limited thereto and that the same may be modified 110 and varied without departing from the spirit of my invention and the domain of the appended claim.

Having thus described my invention, what I claim is:—

In a pneumatic tool, a cylinder, a piston reciprocably mounted in said cylinder, a valve housing, a shoulder formed in said valve housing, a valve piece mounted in said valve housing for controlling the induction 120 of the motive fluid, said valve piece consisting of a hollow member having an annular flange at each extremity, one of said flanges being arranged to close off the induction of the motive to the rear of the piston when the 125 valve piece is in one position, while the other flange is arranged to establish communication of the motive fluid with the cylinder in

front of the piston, the last named flange adapted to rest upon said shoulder of said valve housing while said valve piece is in position to establish communication of the motive fluid with the cylinder in front of the piston, and said last named flange having a relatively small opening therethrough adapted to permit the motive fluid to escape

from the rear of said valve piece when the latter moves rearwardly.

In testimony whereof I affix my signature in the presence of two witnesses.

THOMAS J. BARBRE.
